W. H. Tracy, Attorney

UNITED STATES PATENT OFFICE.

ALBERT WOLF, OF TRAVERSE CITY, MICHIGAN.

FOLDING TOOTH-BRUSH.

1,307,530.

Specification of Letters Patent. Patented June 24, 1919.

Application filed September 6, 1917. Serial No. 190,043.

To all whom it may concern:

Be it known that I, ALBERT WOLF, a citizen of the United States, residing at Traverse City, in the county of Grand Traverse 5 and State of Michigan, have invented certain new and useful Improvements in Folding Tooth-Brushes, of which the following is a specification.

This invention relates to an improved 10 tooth brush and has as its primary object to provide a device of this character which may be folded into compact form to be carried about in the pocket.

The invention has as a further object to 15 provide a tooth brush which, when folded, will be of minimum thickness as well as of minimum length.

And a still further object of the invention is to provide a tooth brush which will be of 20 exceedingly simple construction and may thus be produced at small cost.

Other and incidental objects will appear as the description proceeds and in the drawings wherein I have illustrated the preferred 25 embodiment of the invention and wherein similar reference characters designate corresponding parts throughout the several views:

Figure 1 is an elevation particularly illustrating the sectional construction of the 30 body of the brush, as well as the manner in which the sections of the brush body are hingedly connected,

Fig. 2 is a perspective view showing the 35 brush unfolded ready for use, and

Fig. 3 is a view showing the brush folded and arranged within a case therefor.

In carrying out the invention, I employ a brush body which is split longitudinally to 40 form complementary mating members 10. This brush body may be constructed of any suitable material and at one extremity is reduced in width to form a brush head 11, while the opposite extremity of the body 45 provides a suitable handle for the brush. Set into the brush head 11 are brush bristles 12, a single row of the said bristles being preferably arranged upon each of the members 10 of the body. Connecting the members 10 at a point substantially midway between the ends of the brush body is a suitable hinge 13, preferably countersunk into the confronting side faces of the said members. These members are, therefore, adapt-

ed to be swung transversely away from each other to assume the position shown in Fig. 1 of the drawings, with the outer edges of the said members confronting each other. At the handle extremity of the brush body, the members 10 are formed with relatively short 60 outer sections 14 swingingly connected to the longer inner sections of the said members by hinge joints 15, preferably of the type shown. The outer sections 14 may thus be swung to extend in alinement with the 65 inner sections, as shown in Figs. 1 and 2, with the meeting ends of the several sections abutting. At the same time, the outer sections may be folded upon the inner sections to lie, as shown in Fig. 3 of the drawings, 70 against the inner edges of the said inner sections. At their outer ends, the sections 14 are formed with reduced squared terminals 16 and 17. Pivotaly connected with the terminal 16 is a catch 18 adapted to fit over 75 the terminal 17 for connecting the members 10 of the brush body at the adjacent extremity thereof.

When it is intended to use the brush, the complementary members 10 of the brush body 80 are arranged in the position shown in Fig. 2 of the drawings, with the outer sections 14 of the said members extending longitudinally from the inner sections thereof to complete the brush handle when the catch 18 is 85 engaged with the terminal 17, as previously described, for holding the complementary members of the brush body in position with the inner side faces thereof abutting. In this position of the said members, the rows 90 of bristles 12 will be brought into close relation extending parallel to each other to provide an effective brush. To fold the brush, the catch 18 is first released, when the members 10 of the brush body are swung apart 95 to the position illustrated in Fig. 1 of the drawings. With the said members thus disposed, the device will be of minimum thickness. The outer sections 14 of the members 10 are then swung inwardly to rest against 100 the inner edges of the inner sections of the said members so that the brush will then be of minimum length. In this connection, it will be observed, as shown in Fig. 3, that the outer sections 14 will, when folded, lie within 105 the lines of the outer ends of the bristles 12.

It will therefore be seen that I provide a

very simple and effective construction whereby the brush may be folded into compact form to be carried about within the pocket and preferably, a case 19 is employed 5 to receive the brush when so folded. This case may be formed of any suitable material and is open at its upper end so that the folded brush may be readily inserted therein. The case will thus efficiently protect the 10 brush bristles and, at its lower extremity, is preferably provided with suitable openings for ventilating and draining the said bristles. Furthermore, the case will serve to maintain the complementary members 10 of the brush 15 body folded outwardly as well as to maintain the sections 14 of the said members folded against the inner sections thereof.

Copies of this patent may be obtained for five cents each, by addressing the "Commissioner of Patents, Washington, D. C."

Having thus described the invention, what is claimed as new is:

A tooth brush including thin complementary members hingedly connected at their longitudinal edges and having corresponding end portions thereof providing a brush head and opposite corresponding end portions a handle, bristle tufts carried by the brush head, the members being formed of hingedly connected inner and outer sections normally disposed end to end, and means connecting the outer sections at their outer ends for holding the members in position abutting at 30 corresponding side faces thereof and locking the members against separation.

In testimony whereof I affix my signature.
ALBERT WOLF. [L.S.]
